SWINGING SCAFFOLD

Charles A. Weir, Kansas City, Mo.

Application August 17, 1931. Serial No. 557,449

16 Claims. (Cl. 304—15)

This invention relates to that class of swinging scaffolds for the laying of brick or setting of terra cotta providing the exterior finish of buildings. Such scaffolds may consist of a series of 5 units extending for the full length of the adjacent wall or completely around the building if the same is spaced from other buildings. The units are individually adjustable as to height but the flooring of adjacent units is in loose over- 10 lapping relation so that the flooring connection between units shall remain unbroken. Each unit is carried by a series of inner cables and a corresponding series of outer cables, and there is a connection between each cable and unit in the 15 nature of a jack, which through the action of a lever effects elevation of the unit on the cables. In practice the jacks or "pumps" as the masons usually designate them, of each unit, are successively operated to change the altitude of that 20 particular unit as the progress of the masonry work demands, but no unit is raised enough to break the flooring connection between it and the adjacent units. As at present constructed the flooring of the swinging scaffolds is designed to 25 carry the material which makes the wall, as well as the masons, and the series of suspending cables and jacks at the inner edge of the scaffolds must be reached around by the masons to lay some of the brick within the particular stretch of his 30 station. This is objectionable as it is attended by some inconvenience, especially if he is laying brick or setting terra cotta of light color, as in such event he is more careful to avoid touching the cable which is coated more or less with lubricating oil or grease to protect it from corrosive 35 effects of the weather and to make the operation of the jacks or the like, more dependable. Another objection is that where the mason is compelled to stand on the flooring upon which his 40 material is supported he is required to stoop in picking up each brick or trowel of mortar to such degree that the work is unduly fatiguing and his speed and efficiency is impaired.

The cables of scaffolds of the character indicated are sometimes raised and lowered by winding drums to which the upper ends of the cables are secured, or by winding drums on the scaffold to raise or lower the latter by winding the lower 45 ends of the cables thereon. The three methods mentioned, by the use of jacks for adjusting the scaffold without winding action of the cables, by fixed drums from which the cables are suspended, and by drums on the scaffold, are all old and no claim is made to either of such elevating means 50 per se.

My object broadly stated, is to provide a scaffold of the character depicted, with an auxiliary or supplemental scaffold, disposed inward of and in a lower plane than the main scaffold, so that 55 the mason shall be able to do his wall building

without reaching around any suspending cables, and without being compelled to bend over to a fatiguing degree, each time he reaches for a brick or mortar, a further advantage of the auxiliary lower platform flooring being that it is not obstructed by material and in consequence the workmen are in less danger of a fall upon or off the scaffold. A further object is to provide an auxiliary flooring for the masons, which retains its horizontal position when the main scaffold 65 is tilted laterally inward in the progress of adjustment to raise it to a higher level. Ordinarily such tilting is not sufficient to disturb the masons but might cause a fall if it occurred when a workman was not expecting it and was in an unbalanced position. The successive raising of the 70 ends of each unit causes a slight endwise tilting of the auxiliary flooring, but this tilting action is so slight as to have no unbalancing effect on 75 men or material.

Another object is to provide direct supporting connections between the inner series of suspension cables and the auxiliary flooring, and to impose the load of the main platform or flooring on the inner series of cables through the intermediary of such connections. A still further object is to provide connections between the two platforms whereby the inward lateral tilting action of the main platform shall be limited, and a still further object is to make provision for 80 preventing the fall of the auxiliary platform or the dropping of the inner edge of the main platform in the event a direct support between an inner cable and the auxiliary platform is broken.

With the objects named in view, the invention 85 consists in certain novel and useful features of construction and combinations of parts as hereinafter described and claimed; and in order that it may be fully understood, reference is to be had to the accompanying drawings, in which:—

Figure 1 is an end elevation of a swinging scaffold embodying the invention.

Figure 2 is a fragmentary plan view of one of the scaffolds.

Figure 3 is an elevational view of the scaffold 105 as viewed from a point inward thereof.

Figure 4 is a vertical longitudinal section on the line IV—IV of Figure 1.

Figure 5 is a detail perspective view.

Figure 6 is an end view of a scaffold for wall 110 pointing and clean-up operation.

Referring to the drawings in detail, 1 and 2 indicate brackets which may be of any conventional or other type for connection through jacks or other devices for engagement with series of inner and outer suspension cables 1a and 2a, so that the scaffold can be adjusted upwardly on the cables by so-called lifting jacks, or be lifted by cable-suspending winding drums or 115 winding drums operable from the scaffold. As 120

hereinbefore stated the use of jacks and drums for scaffold adjusting purposes is conventional, and no showing of the jacks or cable-suspending drums is made. The drum for winding up a cable by an operator on the scaffold is indicated generally in Figure 6, but the jacks and cable-suspending drums, form no part, per se of my invention. Each bracket 2 is connected as shown or otherwise to the outer end of a pair of spaced bars 3, it being noted in this connection (see Figure 2), that the cables and related brackets 2 are spaced from the adjacent outer cables and related brackets several feet apart, the distance between them usually being approximately seven feet. The inner brackets and cables are likewise so spaced, and are disposed in transverse alignment with the respective brackets of the outer series, as indicated clearly by Figure 2. For each unit of a scaffold, there are usually three sets of angle bars 3, and they form a support for a series of boards 4 constituting the main platform, the boards being long enough to overlap or underlap those of the adjacent platforms, as customary. As thus far described the scaffold is of conventional construction except that the inner series of brackets are not connected directly to the inner ends of the angle bars as customary. Instead, the inner ends of the angle bars are pivotally connected at 5 to pairs of flanking angle iron brackets of step-like or Z form. Said brackets are disposed with their upper arms 6 and lower arms 7 horizontal, their intermediate arms 8 extending obliquely downward and outward from the inner ends of arms 6 to the outer ends of arms 7. The latter are long enough to project nearly to the building wall to be surfaced with brick, terra cotta, etc., and are equipped with rollers 9 to ride upon such wall and thus hold the main platform, including the suspension means, spaced enough from the building wall to conveniently accommodate the masons who will stand upon the board flooring 10 spanning and supported on the arms 7 of the step-shaped brackets. Upon such platform the masons are not only inward of the main platform but are inward of the inner line or series of cables and the jacks or the like for cooperation with said cables in lifting the inner edge to the level of the previously elevated outer edge of the main platform, the auxiliary platform adjustment accompanying that of the inner edge of the main platform because, as hereinafter appears, the auxiliary platform is directly supported from the inner series of cables.

Obtuse angle shaped straps 11 serve as braces between the rear ends of bracket arms 6 and the lower of arms 8, the lower arms of the braces being bolted at 12 to bracket arms 7 about midway the length thereof. The horizontal flanges of angle bars 3 overlap the corresponding flanges of bracket arms 6 and rounded bosses 13 on the latter serve as antifriction contacts between them, and bolts 14 extend through the overlapping flanges and are equipped with nuts 15 at their lower ends to limit tilting action of the main platform, as indicated by dotted lines Figure 1.

To form the direct support of the auxiliary platform, a substantially J-shaped hanger 16 is attached at its upper end to each bracket 1 or its equivalent, and extends down between the front ends of angle bars 3 and the step-shaped brackets, its lower hook end extending around the outer edge of the auxiliary platform and being secured to and between brackets 17 which are engaged by the bolts 12.

From the foregoing it will be seen that the outer edge of the main platform and the auxiliary platform are respectively directly supported by the cables, but that the inner edge of the former is supported indirectly by the inner cables, through the intermediary of the hangers and the step-shaped brackets, and the fact that the inner part of the main platform is pivoted to the step-shaped brackets permits the scaffold to be raised or lowered without imparting tilting action to the auxiliary platform. A horizontal U-bolt 18 bridges the space between each pair of step-shaped brackets and is secured at its ends to the latter. It stands in front or at the opposite side of the respective hanger from the pivot 5 and thus prevents appreciable swaying of the hanger toward or from the building wall.

In the event a hook of a scaffold or scaffold unit should break below the point of its support from the respective cable, all the weight of part of the auxiliary platform would be imposed on the respective step-shaped brackets. It is desirable therefore to provide a safety catch to substitute for a hanger broken as suggested, although it is apparent that if there are three or more inner cables for each unit, as customary, the failure of one hanger as a support would not result in such unit swinging down at its inner edge to a dangerous or even noticeable extent, as the full load would be instantly assumed by the other hangers. The use of a safety catch is however desirable, especially at the ends of the unit. The safety catch provided consists of a pair of plates 19 pivoted at 20 to the upper part of the hanger or the connection thereof with the cable, and extending diagonally downward and outward between the angle bars and equipped at the lower ends with a cross piece or bolt 21, underlying said angle bars and the arms 6 of the step-shaped brackets, the arrangement being such that if the hanger breaks below the point of attachment of the plates 19, the downward movement or sagging of the inner part of the unit will be instantly arrested by the said plates, which thus take up the weight of the load on the broken hanger.

The main platform is preferably equipped with a guard board 22 to prevent bricks, tools and the like sliding over the outer edge, and such platforms are also equipped with a guard railing and a wire netting extending down from the guard railing to the outer edge of the platform or to the guard board, if equipped with the latter. The auxiliary platform is likewise equipped with a guard board 23 retained thereon at the outer edge by a hook-bolt 24 secured to one of the brackets, and the space between said board and the inner edge of the main platform is preferably closed with wire fabric. The railing for the main platform and wire fabric for both platforms is omitted as the use on the former is old and would be obvious for application on the auxiliary platform.

For what is called clean-up work, such as pointing-up, sand-blasting, tucking, scrubbing, etc., the weight of materials and equipment used will not be great and the outer series of cables, bars 3, main platform and the safety catches can be dispensed with to advantage as the entire weight remaining can be safely sustained by the single inner series of cables. Preliminary to the take-down of adjacent sets of bars 3, the respective pivot pin 5 therefor, must be removed. The pin is replaced in the brackets after the bars are withdrawn, so that it shall be in a position to abut the outer edge of the hanger 16 interposed between said pin and the cross-bolt 18, disposed

- inward of the hanger. Arranged as explained, the pin 5 functions no longer as a pivot, but still retains its function as a stop-pin to check tilting movement in one direction, of the auxiliary platform supporting brackets fulcrumed on the lower and underlying ends of the hangers. By reference to Figure 6, it will be seen that downward movement of the inner edge of platform 10 is checked by abutment of pin 5 against the outer edge of the hanger, and that any tendency of the outer edge of said platform to move downward is checked by the bolt 18 abutting the inner edge of said hanger.
- To avoid the inconvenience of using platform 10 to support sand blast pipes, buckets, tools and the like, it is desirable to provide a narrow platform on the arms 6 of the Z brackets, such platform being represented by one of the boards 4, and to guard against accidental dislodgement of said board and to assist in preventing lateral tilting of the platform 10, each unit may be equipped with standards 25 secured to the outer ends of arms 6 of said brackets and arched forward and attached at their upper ends to the respective cables, and these arched standards for greater security may be connected near the cables by upright braces 26 to the step-shaped brackets near the inner edge of the shelf, as shown by Figure 6. By this arrangement there will be additional security against downward and inward tilting of the auxiliary platform, as any tendency in that direction will be resisted by application of inward lateral pressure on the cables by the upper ends of the arched standards.
- Scaffolds of the general character referred to herein for wall erection or clean-up purposes, are flexible and are either "pumped" up on the cables or the latter are wound on "drums" (see Figure 6), as required to keep the masons at the most convenient height to work on the building wall. The conventional single platform type as hereinbefore stated, carries the entire load of material used in the erection of the wall facing as well as the masons, as distinguished from the scaffold of this invention provided with an auxiliary platform at a lower level and inward of the suspending cables, to give the workmen more convenient access to the building wall, in addition to the other features of advantage pointed out in the statement of the objects of the invention. The type described as for use in clean-up operations represents merely, in its essential features, a sub-combination of the double-platform, with the addition in Figure 6, of added parts to insure greater stabilization and safety in use.
- While I have described and illustrated the preferred embodiments, it is to be understood that the invention is susceptible of modification within the principle of construction and mode of operation involved and within the spirit and scope of the appended claims.
- I claim:—
1. A swinging scaffold, comprising a main platform and an auxiliary platform at one side of and lower than the main platform, an outer series of vertical cables supporting the outer edge of the main platform, an inner series of vertical cables in approximately the plane of the inner edge of the main platform, a series of hangers supported from the inner cables and underlying and supporting the auxiliary platform, brackets underlying both platforms and pivotally connected to the main platform, and means connecting the brackets and main platform outward of the pivotal connection thereof to limit tilting adjustment of said platform relative to said brackets.
  2. A swinging scaffold, comprising a main platform and an auxiliary platform at one side of and lower than the main platform, an outer series of vertical cables supporting the outer edge of the main platform, an inner series of vertical cables in approximately the plane of the inner edge of the main platform, a series of hangers supported from the inner cables and underlying and supporting the auxiliary platform, brackets underlying both platforms and pivotally connected to the main platform, and means connecting the brackets and main platform outward of the pivotal connection thereof to limit tilting adjustment of said platform relative to said brackets.
  3. A swinging scaffold, comprising a main platform and an auxiliary platform at one side of and lower than the main platform, an outer series of vertical cables supporting the outer edge of the main platform, an inner series of vertical cables in approximately the plane of the inner edge of the main platform, a series of hangers supported from the inner cables and underlying and supporting the auxiliary platform, brackets underlying both platforms and pivotally connected to the main platform, and means for transferring support from an inner cable to the inner part of the main platform in the event of loss of support by the respective hanger from said cable.
  4. A swinging scaffold, comprising a main platform and an auxiliary platform at one side of and lower than the main platform, an outer series of vertical cables supporting the outer edge of the main platform, an inner series of vertical cables in approximately the plane of the inner edge of the main platform, a series of hangers supported from the inner cables and underlying and supporting the auxiliary platform, brackets underlying both platforms and pivotally connected to the main platform, and a safety catch supported from each inner cable and underlying the inner part of the main platform.
  5. A swinging scaffold, comprising a main platform and an auxiliary platform at one side of and lower than the main platform, an outer series of vertical cables supporting the outer edge of the main platform, an inner series of vertical cables in approximately the plane of the inner edge of the main platform, a series of hangers supported from the inner cables and underlying and supporting the auxiliary platform, brackets underlying both platforms and pivotally connected to the main platform, and a safety catch suspended from the respective cable and extending downward and underlying the main platform and a part of the adjacent bracket.
  6. A swinging scaffold comprising a series of pairs of cross-bars, a platform resting on and spanning the spaces between adjacent pairs of said bars, a suspension cable for the outer ends of each pair of bars, pairs of brackets pivoted to and near the inner ends of said pairs of bars and depending therefrom and projecting inwardly relative thereto in a lower plane, an auxiliary platform upon the said inwardly projecting portions of said brackets, a series of hangers underlying the auxiliary platform and connected to the adjacent brackets, and a series of suspension cables affording support to said hangers.
  7. A swinging scaffold comprising a series of pairs of cross-bars, a platform resting on and spanning the spaces between said bars, a series of suspension cables for the outer ends of said bars, pairs of brackets pivoted to and near the inner ends of said pairs of bars and depending there-

- from and projecting inwardly relative thereto in a lower plane, an auxiliary platform upon the said inwardly projecting portions of said brackets, a series of hangers underlying the auxiliary platform and disposed adjacent and connected at their lower ends to said brackets, a series of suspension cables affording support to said hangers, and means for preventing the hangers and brackets from independently swinging freely in a direction transversely of the platforms. 80
3. A swinging scaffold comprising a series of pairs of cross-bars, a platform resting on and spanning the spaces between said bars, a series of suspension cables for the outer ends of said bars, pairs of brackets pivoted to and near the inner ends of said pairs of bars and depending therefrom and projecting inwardly relative thereto in a lower plane, an auxiliary platform upon the said inwardly projecting portions of said brackets, a series of hangers underlying the auxiliary platform and disposed adjacent and connected at their lower ends to said brackets, a series of suspension cables affording support to said hangers, means for preventing the hangers and brackets from independently swinging freely in a direction transversely of the platforms, and means supported from the inner cables and extending downward between the adjacent bars of the pairs of angle bars and between the brackets comprising the adjacent pairs thereof, and provided with cross-pins underlying said adjacent pairs of angle bars and brackets in a plane outward of the plane of the series of inner cables. 90
4. A swinging scaffold, comprising a series of hanging cables spaced from a wall, a platform for abutting the wall, a series of hangers for underlying the platform and supported from the respective cables, a series of step-shaped brackets adjacent the respective hangers and underlying and supporting the platform and secured to the lower ends of said hangers, and means to retain the brackets and platform in substantially fixed relation to the hangers. 100
5. A swinging scaffold, comprising a series of hanging cables spaced from a wall, a platform for abutting the wall, a series of hangers for underlying the platform and supported from the respective cables, a series of step-shaped brackets adjacent the respective hangers and underlying and supporting the platform and secured to the lower ends of said hangers, means to retain the brackets and platform in substantially fixed relation to the hangers, and a shelf upon the brackets outward of the hangers. 110
6. A swinging scaffold, comprising a series of hanging cables spaced from a wall, a platform for abutting the wall, a series of hangers for underlying the platform and supported from the respective cables, a series of step-shaped brackets adjacent the respective hangers and underlying and supporting the platform and secured to the lower ends of the hangers, means to retain the brackets in substantially fixed relation to the hangers, and standards secured at their lower ends to the outer ends of the brackets and at their upper ends to the respective cables above the hangers. 120
7. A swinging scaffold, comprising a series of hanging cables spaced from a wall, a platform for abutting the wall, a series of hangers for underlying the platform and supported from the respective cables, a series of step-shaped brackets adjacent the respective hangers and underlying and supporting the platform and secured to the lower ends of the hangers, means to retain the brackets in substantially fixed relation to the hangers, and safety catches secured to the hangers above the plane of the cross-bars and underlying the latter and parts of said brackets. 130
8. In a swinging scaffold, a series of vertically-disposed pairs of step-shaped brackets, a platform spanning the spaces between a plurality of pairs of the brackets and resting upon the arms thereof constituting the lower tread portions, a shelf upon the upper tread portions of the brackets, suspension cables in approximately the plane of the riser portions of the step-shaped brackets, J-shaped hangers disposed between the members of the pairs of brackets and pendently supported from said cables and at their lower ends underlying said platform and secured to said brackets, and means secured to the pairs of brackets and disposed to check independent inward and outward swinging movement of said hangers and brackets. 140
9. In a swinging scaffold, a series of vertically-disposed pairs of step-shaped brackets, a platform spanning the spaces between a plurality of pairs of the brackets and resting upon the arms thereof constituting the lower tread portions, a shelf upon the upper tread portions of the brackets, suspension cables in approximately the plane of the riser portions of the step-shaped brackets, J-shaped hangers disposed between the members of the pairs of brackets and pendently supported from said cables and at their lower ends underlying said platform and secured to said brackets, means secured to the pairs of brackets and disposed to check independent inward and outward swinging movement of said hangers and brackets, and standards connecting the outer ends of the upper tread portions of said brackets with said cables in a horizontal plane above that of the hangers. 150
10. In a swinging scaffold, a series of vertically-disposed pairs of step-shaped brackets, a platform resting on the lower tread portions of a plurality of pairs of the brackets, suspension cables, J-shaped hangers pendently supported from the cables and each disposed adjacent one pair of the brackets and underlying the platform and secured below the latter to the adjacent pair of brackets, and means for preventing independent swinging movement of the brackets and hangers. 160
11. A swinging scaffold comprising a series of pairs of cross-bars, a platform resting on a plurality of the pairs of cross-bars, a suspension cable connected to the outer portions of each pair of said cross-bars, a pair of brackets attached to each pair of cross-bars near the inner ends of the latter and depending therefrom and having portions projecting inwardly relative to and in a lower plane than said pairs of cross-bars, an auxiliary platform resting on the inwardly-projecting portions of adjacent pairs of said brackets, a series of inner suspension cables, a hanger suspended from each inner cable and at the lower end underlying the auxiliary platform and secured to the inwardly-projecting portions of a pair of said brackets, and safety catches secured to the hangers above the plane of the cross-bars and underlying the latter and parts of said brackets. 170
